(57) CLAIM

I claim, the ornamental design for the recordable greeting card, as shown and described.

DESCRIPTION

FIG. 1 is a front elevation view of the recordable greeting card showing my new design;

FIG. 2 is a rear elevation view thereof;

FIG. 3 is a left-side elevation view thereof;

FIG. 4 is a top plan view thereof; and,

FIG. 5 is a perspective view thereof.

The broken line showing of parts of the drawings is included for the purpose of illustrating use and environment and forms no part of the claimed design.
